MILK BOTTLE SAFE

Thomas S. Collins, Akron, Ohio

Application December 7, 1933, Serial No. 701,371

1 Claim. (Cl. 232—41)

One object of this invention is to provide a safe within which bottles of milk and the like may be held in security during the interval that elapses between the depositing of the bottles by the milk man, and the removal of the bottles by the customer. Another object of the invention is to provide novel means for locking and controlling the doors which give access to the casing which contains the milk bottles. A further object of the invention is to improve the construction of the casing. Yet another object of the invention is to provide novel means whereby one of the doors may be opened from within a house, at the will of the person who has purchased the milk. A further object of the invention is to provide novel means for mounting the casing.

It is within the province of the disclosure to improve generally and to enhance the utility of devices of that type to which the invention applies.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in top plan, a device constructed in accordance with the invention, parts being in section;

Fig. 2 is a horizontal section of the casing;
Fig. 3 is a section on the line 3—3 of Fig. 2;
Fig. 4 is a section on the line 4—4 of Fig. 2;
Fig. 5 is a section on the line 5—5 of Fig. 2;
Fig. 6 is a fragmental transverse section showing a slight modification.

The device forming the subject matter of this application may be used in a wide variety of ways, and may be mounted as desired, without departing from the spirit of the invention. By way of illustration, however, there is shown in Fig. 1, the vertical wall 1 of a building. In the wall 1, on the inside of the house, a guide 2 is mounted.

In Fig. 1, the device described is shown as being located outside of the building. The device embodies a box-like casing 3, which may be of rectangular outline. The casing 3 comprises a body 4, open at both ends, but adapted to be closed, at those ends, by doors 8 and 11, which will be described hereinafter. On the top of the body 4 of the casing 3 may be placed a rack 5, of any desired

construction, adapted to hold empty bottles and the like.

Figure 2 shows that the inner wall of the body 4 is provided with holes 6, adapted to receive studs 7, whereby the casing 3 is secured to the outer surface of the wall 1, in a substantially horizontal position.

At one end of the body 4 there is a first or intake door 8, hingedly mounted at 9, to swing horizontally on the inner surface of the door 8 (Fig. 5) near to the free edge of the door (Fig. 5) there is an inwardly extended keeper 10. A delivery door 11 is hinged at 12 to the opposite end of the body 4, to swing horizontally.

Discussing the locking mechanism for the door 15 8, it will be observed that, as shown in Fig. 3, for instance, a latch 14 is provided, the latch being supplied at one end with a bevelled head 15 adapted to engage automatically with the keeper 10 on the door 8. The latch 14 is carried at one end, for vertical swinging movement, on a fulcrum element 16 mounted in the outer side wall of the body 4 of the casing 3, a spacer 17 (Fig. 2) being mounted on the fulcrum element 16, between the said wall of the casing and the latch 25 14. That end of the latch 14 which carries the head 15 slides vertically within a guide 18 on the wall of the body 4, as Fig. 3 will disclose.

The latch 14 is raised to the inoperative position of Fig. 3 through the instrumentality of an arm 19, provided at its upper end with a longitudinal slot 20, in which works a pivot element 21 carried by the latch 14. It can be seen in Fig. 5, that the arm 19 has an inwardly extended, angularly disposed foot 22, attached by a securing element 23 to a vertically movable platform 24, located within the body 4 and substantially coextensive in area with the body. The securing element 23 projects some little distance below the platform 24, as Figs. 3 and 5 will show.

The platform 24 is hingedly mounted, near to its inner edge, for vertical swinging movement. The means for thus hinging the platform 24 may be of various kinds. For instance, the platform 45 may be mounted on studs 25, secured to the bottom of the body 4 of the casing 3, spacers 26 being interposed between the bottom of the body and the platform 24. The mounting of the platform 24 on the studs 25 is loose enough so that the platform 24 can have the aforesaid vertical 50 swinging movement. A spring means is provided for raising the free edge of the platform 24, and this means may be of any desired sort. By way of illustration, an inwardly extended leaf spring 27 is shown in Fig. 5. The inner end of the leaf 55

spring 27 bears on the bottom of the body 4, and the outer end of the leaf spring is attached by a securing device 28 to the platform 24. The leaf spring 27 is located between the platform 24 and the bottom of the body 4.

There is a keeper 29 (Figs. 2 and 4) on the outer wall of the body 4 of the casing 3. With this keeper 29, the horizontal arm 30 of a bell crank latch 31 is adapted to cooperate, to hold the door 11 closed. The bell crank latch 31 is fulcrumed at 32 on the door 11, and includes a depending vertical arm 34, the horizontal arm 30 of the bell crank latch working in a guide 33 on the door 11. In the lower portion of the vertical depending arm 34 of the bell crank latch 31 an elongated slot 35 is formed.

It can be seen in Fig. 4, that the slot 35 in the arm 34 of the latch 31 receives a pivot element 36, carried by the inner end of a slide 37, mounted for right line reciprocation in guides 38 on the inner surface of the door 11. A pull spring 39 is attached at one end to the intermediate portion of the slide 37, the opposite end of the pull spring being attached to the innermost guide 38. In general, however, the spring means for operating the slide 37 may be constructed as desired. Figure 2 shows that the inner end of the slide 37 has a rectangularly disposed finger 40, mounted in the path of a means under the control of an operator for actuating the slide 37. The aforesaid means may be a plunger 41, mounted for straight line reciprocation in the wall 1 and in the guide 2 of Fig. 1, the plunger 41 being supplied at its inner end with a push button 42, disposed within the house.

When the device is in condition to receive milk bottles at the hand of the milk man, the positions of the various parts are as follows:

The spring 27 of Fig. 5 elevates the platform 24, 40 the platform swinging upwardly on the studs 25 of Fig. 4. The arm 19, which is attached at 23 to the platform 24 is raised. The pivot element 21 in the latch 14 is at the lower end of the slot 20 in the upper end of the arm 19, and the latch 14 is raised, so that its head 15 is out of engagement with the keeper 10 on the intake door 8. The intake door 8 may be swung open on its hinges 9, to permit the milk man to place the bottles in the casing 3, on the platform 24.

50 The spring 39 of Fig. 4 has moved the slide 37 to the right in Fig. 4, the pivot element 36 on the slide has tilted the bell crank latch 31 on its fulcrum 32, and the horizontal arm 30 of the latch is engaged with the keeper 29 on the body 4 (Fig. 2), the delivery door 11 thus being latched in a closed position.

The intake door 8 is unlatched, as in Fig. 3, and may be opened. The milk man then places the bottles on the platform 24, and the weight 60 of the bottles and their contents causes the platform 24 to swing downwardly on the studs 25, overcoming the action of the spring 27. As the platform 24 moves downwardly, the arm 19 moves downwardly with it, because the arm is attached

to the platform. The pivot element 21 in the latch 14 no longer has supporting engagement with the arm 19, at the lower end of the slot 20, and the latch 14 can swing downwardly to such a position that, when the intake door 8 is closed, 5 the keeper 10 on the said door will engage automatically with the head 15 of the latch 14 and hold the door closed. The downwardly projecting end of the securing member 23 of Figs. 5 and 3 limits the downward swinging movement of 10 the platform 24 on the studs 25.

As matters stand, at this point of the description, the milk bottles are inside the casing 3, on the platform 24, the intake door 8 is latched in a closed position, and the delivery door 11 is latched 15 in a closed position.

When the operator or purchaser wishes to get his milk, he shoves outwardly on the plunger 41 by means of the button 42. The plunger 41 engages the finger 40 of the slide 37 and moves the 20 slide to the left in Fig. 4, against the action of the pull spring 39. The pivot element 36 on the slide 37 tilts the bell crank latch 31 on its fulcrum 32 and disengages the horizontal arm of the bell crank latch from the keeper 29 on the side of the 25 body 4. The delivery door now is set free, and may be opened. The purchaser takes out the milk bottles, and when they are removed from the platform 24, the platform is raised by the spring 27, the parts being restored to the position of Fig. 3, and the intake door 8 being released, so that it can be opened for the introduction of milk bottles, upon occasion. When the delivery door 11 is closed, the mechanism shown in Fig. 4 latches or locks the door in closed 30 position.

For those who do not care for the plunger 41 and the latching mechanism for the door 11 shown in Fig. 4, a simpler means is disclosed in Fig. 6. In that figure, parts hereinbefore described have been designated by numerals previously used, with the suffix "a". Here the delivery door 11a carries a key-operated lock 43, the bolt 44 of which may be engaged with a keeper 45 on the body 4a of the casing 3a.

Having thus described the invention, what is claimed is:

In a milk bottle safe, a casing comprising a body and a door hingedly mounted on the body, a keeper on the body, a latch mechanism carried by the door and engageable with the keeper, the latch mechanism embodying a slide mounted on the door and having an offset finger, a plunger mounted in the body for advancement at the will of an operator, to engage the finger, first to 50 operate the slide and disengage the latch mechanism from the keeper, and then to swing the door toward open position, and spring means for reTRACTING the slide, to dispose the latch mechanism in such position that it will engage the keeper 60 when the door is closed, the plunger being moved outwardly by the retracted slide, when the door is closed.

THOMAS S. COLLINS.
